E. N. HENNEGAN,
AMUSEMENT DEVICE.
APPLICATION FILED MAY 29, 1920.

1,395,674.

Patented Nov. 1, 1921.

INVENTOR:

Eva N. Hennegan,

BY *Arthur H. Ewald,*
ATTORNEY.

UNITED STATES PATENT OFFICE.

EVA N. HENNEGAN, OF CINCINNATI, OHIO.

AMUSEMENT DEVICE.

1,395,674.

Specification of Letters Patent.

Patented Nov. 1, 1921.

Application filed May 29, 1920. Serial No. 385,319.

To all whom it may concern:

Be it known that I, EVA N. HENNEGAN, a citizen of the United States, and resident of Cincinnati, in the county of Hamilton 5 and State of Ohio, have invented certain new and useful Improvements in Amusement Devices, of which the following is a full, clear, and exact description, reference being had to the accompanying drawings, forming 10 a part of this specification.

My invention relates to amusement devices, and particularly to an apparatus or game for the foretelling of future events.

The principal object of the present invention is to provide game apparatus for the forecasting of future events, the operation of which will contribute to the amusement of one or more individuals.

Further objects of the present invention 20 will appear from the following description thereof.

In the drawings:

Figure 1 is a plan view of the invention;

Fig. 2 is a section on line 2—2 of Fig. 1; 25 Fig. 3 is a plan view of the base or fixed member of the device;

Fig. 4 is a perspective of a portion of the device.

The numeral 1 indicates the base or fixed 30 member of apparatus constructed in accordance with this invention. The same is constructed either of heavy cardboard, wood or other suitable material, and is preferably circular in outline. The member 1 has a 35 circular upwardly extending flange 2. Rotatably mounted on a pivot 3 in the member 1 is the movable or active member 4 of the device. The member 4 is constructed of material similar to that of the member 1, and 40 is of such thickness that when mounted the surface thereof will be flush with the flange 2 of the member 1. The member 1 is provided just inside the flange 2 with a series 45 of circles 5 within each of which is a numeral as shown in Fig. 2 of the drawings. Along the flange 2 opposite the circles 5 are points 6 arranged to indicate the respective circles 5.

The surface of the member 4 is divided by 50 an ornamental design printed thereon into a plurality of divisions 7, each of which discloses a different color; in the exemplification of the invention illustrated in the drawings, six of such divisions are shown, having the following colors: blue, yellow, green, 55 red, orange and brown. Each of the divi-

sions is provided with spaces 8 having numerals corresponding to numerals in the circles 5 on the member 1. Each of the spaces 8 is further provided with suitably printed matter for the foretelling of some future 60 event. The numerals in the several divisions are duplicates of each other, but the related reading matter is different in the several divisions. The circles 5 on the member 1 are printed in colors corresponding to the 65 colors of the divisions 7, but the colors in the circles 5 are irregularly distributed throughout the several circles.

When the members 1 and 4 are assembled as shown in Figs. 1, 2, and 4, the circles 5 70 on the member 1 are covered by the member 4. The member 4 is provided with an opening 9 of size corresponding to the circles 5, and positioned on the member 4 so as to be adapted to rest over either of the circles. 75 Mounted on the member 4 over the opening 9 is a plate 10 having an indicating point 11. The plate is hinged or folded as shown at 12 so that it may be turned back to uncover the opening. 80

The operation of the device is as follows: The player gives the member 4 a turn so that the same rotates on the pivot 3. The member is permitted to rotate until it comes to a rest with the point 11 opposite one of the 85 indicia 6. When in such a position the opening 9 will rest over one of the circles 5. The point 11 is then raised to disclose the numeral as well as the color of the circle 5 under the opening. This having been ascertained, for example, as shown in Fig. 4 the disclosed numeral is 7 in a red circle, the player next refers to the red division on the member 4 and the space 7 thereon, and the reading matter within said space is, according 90 to the rules, supposed to indicate some future event in his life. As will be understood any number of players may participate in the game, and the simulated predictions are of such a nature as to contribute 100 to the amusement of the players.

Having thus fully described my invention, what I claim as new and desire to secure by Letters Patent, is:

1. An amusement device comprising a 105 base member, indicia arranged in a circle on said base member, each indicium being associated with one of a plurality of colors, a rotatable member mounted on said base member, said rotatable member being pro- 110

- vided on its face with divisions each of which is colored to correspond with one of the colors of said indicia, spaces in each of said divisions, each of the spaces being provided with an indicium corresponding to certain indicia on the base member and being also provided with printed matter, and a pointer on the rotatable member for indicating an indicium on the base member.
- 10 2. An amusement device comprising a base member, indicia arranged in a circle on said base member, each indicium being associated with one of a plurality of colors, a rotatable member mounted on said base member, said rotatable member being arranged to cover said indicia, and being provided on its face with divisions each of which is colored to correspond with one of the colors of said indicia, spaces in each of said divisions, each of the spaces being provided with an indicium corresponding to certain indicia on the base member and being also provided with printed matter, a movable pointer on the rotatable member for indicating an indicium on the base member, and an opening in said
- 15 3. An amusement device comprising a base member, indicia arranged in a circle on said base member, each indicium being associated with one of a plurality of colors, a rotatable member mounted on said base member, said rotatable member being arranged to cover said indicia, and being provided on its face with divisions each of which is colored to correspond with one of the colors of said indicia, spaces in each of said divisions, each of the spaces being provided with an indicium corresponding to certain indicia on the base member and being also provided with printed matter, a movable pointer on the rotatable member for indicating an indicium on the base member, and an opening in said rotatable member through which the indicium may be read, said opening being normally covered by said pointer, and being arranged to be uncovered by the moving of the pointer.
- 20 4. An amusement device comprising a base member, indicia arranged in a circle on said base member, each indicium being associated with one of a plurality of colors, a rotatable member mounted on said base member, said rotatable member being arranged to cover said indicia, and being provided on its face with divisions each of which is colored to correspond with one of the colors of said indicia, spaces in each of said divisions, each of the spaces being provided with an indicium corresponding to certain indicia on the base member and being also provided with printed matter, a movable pointer on the rotatable member for indicating an indicium on the base member, and an opening in said rotatable member through which the indicium may be read, said opening being normally covered by said pointer, and being arranged to be uncovered by the moving of the pointer.
